DESIGN FOR A SUPPORT FOR FIREPLACE TOOLS OR THE LIKE

Lewen R. Nelson, Peoria, Ill.

Application February 23, 1940, Serial No. 90,457

Term of patent 14 years

To all whom it may concern:

Be it known that I, Lewen R. Nelson, a citizen of the United States, residing at Peoria, in the county of Peoria and State of Illinois, have invented a new, original, and ornamental Design for a Support for Fireplace Tools or the Like, of which the following is a specification, reference being had to the accompanying drawing, forming part thereof.

Figure 1 is a perspective view of the support, for fireplace tools or the like, showing my design; Figure 2 is an end elevational view; and Figure 3 is a top plan view.

I claim:

The ornamental design for a support for fireplace tools or the like, as shown.

LEWEN R. NELSON.
